UNITED STATES PATENT OFFICE

HARRY J. CRINER, OF DAVENPORT, IOWA, ASSIGNOR OF ONE-HALF TO A. G. BUSH, OF DAVENPORT, IOWA

WASHING MACHINE

Application filed October 31, 1927. Serial No. 229,928.

My invention relates to improvements in washing machines and the objects of my invention are:

1. To provide a washing machine having a movable perforated clothes container mounted within the tub of the machine;
2. To provide means for giving to such container a reciprocating vertical motion and a horizontal, reciprocating rotary motion simultaneously;
3. To provide a mechanical movement which will transmit from a crank shaft a reciprocating rotary and a reciprocating longitudinal movement simultaneously, to a shaft;
4. To provide simple means for increasing the flowage of the water through the clothes in a washing machine.

I attain these objects by the means illustrated in the accompanying drawings, in which,—

Figure 1 is a vertical section of a washing machine containing my improvement, on the line 1—1 of Figure 2, but showing the gear housing and wringer drive shaft housing in elevation; Fig. 2 is a cross section on the line 2—2 of Figure 1; Fig. 3 is a detail view of the bottom of the crank mechanism; Fig. 4 is a detail showing a side view of the crank mechanism with the socket member of the swivel in section; Fig. 5 is an enlarged sectional detail of the upper end of the drive shaft and the tubular member of the clothes receptacle; Fig. 6 is a cross-sectional view on the line 6—6 of Figure 5; Fig. 7 is a sectional detail on the line 2—2 of Figure 1 showing a modified form of clutch which may be utilized to drive the swivel crank but showing the clutch and rocker shaft and the main drive shaft in full; Fig. 8 is a sectional detail showing an alternate form of the top of the tub; Fig. 9 is a detail side elevation of the clutch shown in Figure 7; Fig. 10 is a detail of an alternate form showing the sleeve, 57^a, of the arm, 2^a, splined to the shaft, with splines, 57^b, and with collars, 57^c, adjacent thereto, the sleeve, 57^a, being in section.

My preferred form of washing machine comprises a circular base housing or hollow support, 55', supported upon brackets, 17,

and casters 17^a, which may be secured to the base housing in any of the common methods.

The housing 55', is preferably made of light sheet metal and a heavier base plate, 15, is secured therein to which is bolted a supporting column, 11, the upper end of which is bolted to the circular plate, 56, which forms the top of the base housing, 55', and also the bottom of the tub, 37.

A tube, 44, is secured in the upper end of the column, 11, and the lower end thereof is secured against upward movement by the lock nut, 12, which is threaded upon the lower end of the tube, 44. A bushing, 49', is secured around the tube, 44, within the lower end of the column, 43, upon which the column, 43, revolves. This bushing may also be threaded or otherwise suitably secured to the tube, 44, to secure same against downward movement.

A bearing plate, 52, is bolted to the bottom, 56, of the tub, and forms a stuffing box to prevent leakage around the tube, 44. The tube, 44, extends upwardly above the water level of the tub, 37, and its upper end is fitted with a bearing block, 46.

A bearing, 13, is united to the base, 15, and a rod, 10, is slidably mounted within the bearings, 46 and 13, at the upper end of the rod, 10, a square head, 45, is secured by a pin, 49, which fits into the upper end of the column, 43. Packing rings, 46 and 51, are secured around the shaft, 10, to prevent leakage and may be of any suitable material and secured to the tube, 44, by any suitable means.

The lower end of the column, 43, is bolted or otherwise secured to the bottom plate, 50, of a perforated basket or container in which the clothes are placed to be washed and perforations, 41, are formed in the side walls and bottom of the basket or container, 39.

Transverse vanes, 42, are secured within the basket or container, 39, and the upper edge of the container is preferably formed in a roll, 38, which may be hollow or formed with a wire cord.

A sleeve, 57, is secured upon the rod, 10, by a key or pin, 60, and the sleeve, 57, has formed integral therewith, an arm, 2, the 100

outer end of which is shaped in the form of a bolt.

5 A motor, 9, has its base, 4, bolted to the base, 15, and has its shaft, 68, fitted with a small gear, 67, which meshes with a large gear, 66, mounted upon the horizontal shaft, 52.

10 A crank of novel form is secured to the shaft, 52. This crank comprises a swivel housing, 8, which may be secured upon the shaft, 52, by a pin or key, 20, as shown in Figure 2, or may be loosely mounted upon the inner end of the shaft, 52^a, and secured by a nut, 26, threaded upon the inner end of the 15 shaft with a sliding clutch member, 24, interposed between the swivel housing, 8^a, and the housing, 6, of the gear wheel, 66, as shown in Figure 7, the sliding clutch member, 24, being splined to the shaft, 52^a, and being 20 embraced by a yoke or fork, 25, mounted in a suitable bearing, 17, united to the gear housing, 6, or other suitable support and operable by a rocking-bar, 18. The swivel housing, 8, has its body made in a channeled 25 form as shown in Figure 3 and a swivel, 53, is pivoted to the flanges of the swivel housing, 8, upon the pin, 58, which is preferably located in a line with the longitudinal axis of the shaft 52.

30 The swivel, 53, has a separable section 54, secured thereto by a bolt, 56, and the body, 53, of the swivel, combined with the separable portion, 54, forms a socket which receives the ball, 55, formed upon the outer end 35 of the arm, 2, thus forming a ball and socket joint. The outer end of the shaft, 52, is provided with a bevel gear wheel, 63, adapted to drive a corresponding bevel gear, 62, upon the wringer drive shaft, 61, mounted within 40 the housing, 23.

The top of the tub may be formed with an inwardly projecting annular portion, 36, sloping downwardly toward the center and with a downwardly extending flange, 47, 45 upon its inner edge and with a rolled or beaded portion, 48, at its outer edge. This form of top will tend to prevent splashing and will readily return any splashed water to the tub. Any desired form of cover may 50 be used in connection with this construction. I make no claim for any particular form of cover.

I prefer, however, to form the top of the tub with a flanged and beaded edge as shown 55 in the detail Figure 8 so that the top of the tub will not obstruct the removal of the clothes receptacle.

In the operation of this machine, a tub, 37, is first filled with water to the desired height. 60 The clothes are then placed in the basket or receptacle, 39, and the cover put on the machine and the motor started. As the motor drives the crank shaft, 52, the clutch rocking-bar 18, may be operated to throw the 65 clutch member, 24, into engagement with the

swivel housing, 8^a, and this will cause the crank to turn with the crank shaft. The socket member of the crank will carry the head or ball, 55, in an undulating, circular path having a variable plane and will cause the shaft, 10, to reciprocatingly rotate for approximately one-quarter of its circumference and at the same time will cause the shaft, 10, to slide up and down for a distance corresponding to the throw of the crank.

70 In ordinary practice, a crank length of an inch and a half to two inches, giving the clothes receptacle a vertical movement of three or four inches, will be sufficient. At the same time, the clothes receptacle will reciprocatingly rotate for about one-quarter of its circumference.

75 It is obvious that as the receptacle, 39, rises, it will cause the water to pass downwardly through the clothes in the receptacle and that 80 as the receptacle is lowered the water will enter it through the perforations in the bottom and tend to pass through the clothes therein in an upward direction. At the same time that this motion of the water is 85 taking place, the rotary motion of the receptacle will cause more or less rotary motion or circulation of the water within the tub and that the reciprocating rotary motion of the receptacle, with its vanes, 42, will cause a 90 very considerable agitation and movement 95 of the water through the clothes. The various movements of water, clothes and receptacle will also cause a considerable admixture 100 of air with the water the bubbles from which will accelerate the cleansing action of the water upon the clothes.

105 When desired to operate the wringer without operating the washing machine proper, the rocking-bar can be thrown so as to disengage the clutch member, 24. I prefer to mount a weighted head upon the outer end of the rocking-bar 18, upon an arm turned at right angles thereto so that the weight of this head will hold the clutch (shown in Figure 7) in or out of engagement 110 as the case may be, but any other suitable means may be utilized as detents for the clutch.

115 It is obvious that the form and proportions of the various parts of my apparatus may be varied within a wide range without departing from the spirit of my invention and that my crank arrangement may be applied as a mechanical movement to a large 120 variety of mechanical appliances.

125 It is obvious that the form of construction shown will permit the clothes receptacle to be readily removed from the upper end of the shaft for cleaning purposes and when the top of the tub is constructed in the form shown in Figure 8, the entire clothes receptacle may be readily lifted out of the tub.

130 In Figure 10 I have illustrated the use of splines to secure the arm, 2, to the shaft, 10,

and also collars, 57', secured to the shaft, 10, by set screws. It is obvious that the splines or the set screws may be omitted when it is desired to do away with the rotational or vertical movement of the shaft, 10.

5 I claim:

1. A washing machine comprising a hollow support, a tub mounted upon said hollow support, a tube united to the hollow support and extending upwardly into the tub, a shaft 10 slidably and rotatably mounted in the tube, a perforated clothes receptacle having vanes secured therein mounted upon the shaft within the tub, an arm rigidly united to the shaft below the tub, a crank and crank shaft mounted in the hollow support adjacent the free end of the arm, and a ball and socket joint uniting the arm and crank.

15 2. A washing machine comprising a hollow support, a tub mounted upon said hollow support, a tube united to the support and extending upwardly into the tub, a vertical shaft slidably and rotatably mounted in the tube, a perforated clothes receptacle having 20 vanes secured therein, united to the shaft within the tub, and means for imparting simultaneous reciprocating rotary and reciprocating vertical motions to the vertical shaft.

25 3. A washing machine comprising a hollow support, a tub mounted upon said support, a tube united to the support and extending upwardly into the tub to a point above the water line, a vertical shaft slidably and rotatably mounted in the tube, a perforated clothes receptacle having vanes secured therein, united to the shaft within the tub, and means for simultaneously imparting reciprocating rotary and vertical motions to the vertical shaft, comprising an arm rigidly 30 united to the shaft below the tub, a crank and crank shaft mounted in the support adjacent the free end of the arm, and a universal joint uniting the arm and crank.

40 4. A washing machine comprising a cylindrical housing, a tub mounted upon said cylindrical housing in which the bottom of the tub is formed integral with the top of the housing, a tube united to the housing and extending upwardly into the tub, a vertical shaft slidably and rotatably mounted in the tube, a perforated clothes receptacle having vanes secured therein, united to the shaft within the tub, and means for imparting simultaneous reciprocating rotary and reciprocating vertical motion to the vertical shaft comprising an arm rigidly united to the shaft below the tub, a crank and crank shaft mounted in the support adjacent the free end of the arm, and a ball and socket joint uniting the arm and crank.

45 5. A washing machine comprising a tub mounted upon a suitable support, a tube united to the support and extending upwardly into the tub to a point above the water line, a vertical shaft slidably and rotatably

mounted in the tube, a perforated clothes receptacle having vanes secured therein, united to the shaft within the tub, and means for simultaneously imparting reciprocating rotary and vertical motion to the vertical shaft comprising 70 an arm rigidly united to the shaft below the tub, a crank and crank shaft mounted in the support adjacent the free end of the arm, and a ball and socket joint uniting the arm and crank.

75 6. A washing machine comprising a tub mounted upon a suitable support, a tube united to the support and extending upwardly into the tub, a vertical shaft slidably and rotatably mounted in the tube, a perforated clothes receptacle having a central column 80 united thereto, the upper end of which column is mounted upon the upper end of the shaft, an arm rigidly united to the shaft below the tub, a crank and crank shaft mounted in the support adjacent the free end of the arm and a ball and socket joint uniting the arm and crank.

85 7. A washing machine comprising a tub mounted upon a suitable support, a tube 90 united to the support and extending upwardly into the tub, a vertical shaft slidably and rotatably mounted in the tube, a perforated clothes receptacle having a central column 95 united thereto, the upper end of which column is mounted upon the upper end of the shaft, vanes secured in the receptacle, and an arm rigidly united to the shaft below the tub, a crank and crank shaft mounted in the support adjacent the free end of the arm and 100 a ball and socket joint uniting the arm and crank.

In testimony whereof he affixes his signature.
